UNITED STATES PATENT OFFICE

CHARLES A. ANTHONY, OF NEW YORK, N. Y., ASSIGNOR, BY MESNE ASSIGNMENTS,
TO METAL PACKAGE CORPORATION, OF NEW YORK, N. Y., A CORPORATION OF
DELAWARE

CONTAINER

Application filed October 15, 1927. Serial No. 226,313.

My invention relates to containers, preferably of the sheet metal type, the principal object of the invention being to provide a container adapted to hold a plurality of objects such as candy or cigarettes, etc., which shall be so constructed as to effectively serve as an ash tray when the contents have been removed.

A further object of the invention is the production of a container of the type specified having a removable cover provided with means for receiving and supporting cigars, cigarettes or pipes.

A further object of the invention is the production of a container of the above type the cover of which shall be provided with an opening through which ashes or refuse may be poured when the container is used as an ash tray but which is normally closed by a plate of any material but preferably of a transparent material such as fiber glass which interfits with the cover and which acts as a seal. When a transparent material is employed, inspection of the contents of the container through the opening and without removing the cover is possible.

Other and further objects and advantages of the invention will appear from the accompanying description, the invention consisting in the novel container hereinafter more particularly described and then specified in the claims.

In the accompanying drawings illustrating a practical embodiment of the invention:

Fig. 1 is a front elevation (partly in section) of a container constructed in accordance with the invention.

Fig. 2 is a top plan view of the container parts being partially broken away.

Fig. 3 is a front elevation of the upper portion of the container showing it being used as a cigar and cigarette holder after the contents have been removed.

Referring to the several figures of the drawing:

1 indicates the body of the container which may be cylindrical or of any other desired configuration. The body is provided with a bead 2 adjacent the top thereof which is adapted to provide a seat and stop for the

lower edge of a cover, to be presently described, when the cover is applied to the body.

3 indicates the top wall of the cover which is provided with a depending annular flange 4 having a bead 5 at its lower edge. The periphery of said flange 4 is corrugated as illustrated, for the purpose of gripping the same and said bead 5 is provided at spaced intervals with a plurality of depressed portions 6 which act as locking members for detachably retaining the cover on the body as will be described. The body 1 above the bead 2 is provided with outwardly-pressed inclined ridges 7 spaced apart and each of which has one or more lugs 8 thereon. To detachably apply the cover to the body the locking members 6 are brought into alignment with the spaces intermediate the pressed-out ridges 7 and the cover pressed downwardly and then rotated whereby the locking members 6 are brought beneath the pressed-out ridges 7 until they engage the lugs 8, said lugs acting as stops to prevent further rotation of the cover and hold it in locked position as is obvious. This construction whereby the cover is detachably secured to the body is old in the art, however, and forms no part of the present invention. As is manifest any other and suitable means may be employed to detachably fasten the cover to the body.

The cover 3 is provided with a centrally disposed opening 9 in the top wall thereof and with a plurality of downwardly-pressed grooves 10 inclined towards and meeting said opening and being of a configuration adapting them to receive and support cigars, cigarettes or a pipe. Fitting within the cover and engaging the inner side of the flange 4 thereof is an annular washer 11 preferably of a compressible material such as paper providing a seat for a removable plate 12 which in the form of the invention illustrated is in disc form, the periphery of which also engages the inner side of the flange 4.

The corrugations in the flange 4 in a measure bite into the peripheries of the washer 11 and plate 12 and tend to retain them in proper position within the cover. The thickness of the washer 11 is such as to permit the plate 12 to lie perfectly flat thereon

without interference with the grooves 10 and thereby provide an air-tight and sealed container which obviously would not be possible if too thin a washer or no washer at all were used as the plate then would engage the undersides of the inclined grooves 10 which vary in depth throughout their length and the plate then would rock on said grooves.

The container may be used for cigarettes as illustrated in the drawings or for other articles or commodities and I prefer to form the plate 12 of fiber glass or other transparent material whereby the contents of the container may be inspected through the opening 9 for display purposes. When the contents have been removed the container may be used as an ash tray as illustrated in Fig. 3.

What I claim as my invention is:

- 20 1. A container comprising a body and a removable cover therefor provided with an upper wall, said cover having an opening located in said upper wall and a groove formed in said wall for retaining an object, a washer fitting within said cover, a plate seated on said washer and means for detachably holding said cover to said body.
- 25 2. A container comprising a body and a removable cover therefor provided with an upper wall, a corrugated flange on said cover, said cover having an opening located in said upper wall, a washer seated within said cover and engaging the corrugations of said flange and a plate fitted on said washer and closing said opening and also engaging the corrugations of said flange.
- 30 3. A container comprising a body and a removable cover therefor provided with an upper wall, said cover having an opening in said upper wall, a groove in said wall for retaining an object, a washer fitted within said cover and a transparent plate seated on said washer.
- 35 4. A container comprising a body and a removable cover therefor provided with an upper wall, said cover having an opening extending through said upper wall, grooves formed in said wall for retaining an object and a removable plate in said cover normally closing said opening but permitting said container to be used as a refuse receiver without removal of said cover after said plate has been removed therefrom.

Signed at New York, in the county of New York and State of New York, this 10th day of Oct., A. D. 1927.

CHARLES A. ANTHONY.
